UNITED STATES PATENT OFFICE.

ADOLPH R. FADNESS, OF VELVA, NORTH DAKOTA.

ADJUSTABLE SIEVE-HOLDER FOR THRESHING-MACHINES.

1,383,918.

Specification of Letters Patent.

Patented July 5, 1921.

Application filed July 30, 1920. Serial No. 400,052.

To all whom it may concern:

Be it known that I, ADOLPH R. FADNESS, a citizen of the United States, residing at Velva, in the county of McHenry and State 5 of North Dakota, have invented new and useful Improvements in Adjustable Sieve-Holders for Threshing-Machines, of which the following is a specification.

This invention relates to threshing machines, particularly to attachments therefor, and has for its object the provision of means associated with the sieves located beneath the lower chaffer whereby the sieves may be adjusted toward or away from the 15 chaffer, depending upon conditions arising in the threshing of different grains.

An important object is the provision of a device of this character which is so constructed that the sieves may be adjusted 20 from the outside of the machine and even while the machine is in operation, means being also provided whereby the position of the sieves may be readily ascertained at all times.

25 Another object is the provision of a device of this character in which the parts will be held firmly in adjusted position.

An additional object is the provision of a device of this character which will be simple 30 and inexpensive in manufacture and installation, highly efficient in use, durable in service, and a general improvement in the art.

With the above and other objects and advantages in view, the invention consists in the details of construction to be hereinafter more fully described and claimed and illustrated in the accompanying drawings in which—

40 Figure 1 is a side elevation of a portion of a threshing machine, showing my device in position,

Fig. 2 is a longitudinal sectional view 45 through a portion of the threshing machine and showing one side of my adjusting means in elevation,

Fig. 3 is a similar view showing my device also in section,

Fig. 4 is a horizontal sectional view,

50 Fig. 5 is a cross sectional view taken through both sides of the thresher,

Fig. 6 is a fragmentary view illustrating a slight modification,

Fig. 7 is a longitudinal sectional view 55 showing another modified form,

Fig. 8 is a cross section therethrough, and

Fig. 9 is a detail sectional view of a further modification.

Referring more particularly to the drawings, the letters A and B designate the sides 60 of a portion of a threshing machine and C designates the sides of the lower chaffer. The letters D and E designate the sides of the sieves which are pivoted at one end, as shown at F. It is well known that under 65 different conditions arising in the threshing of different grains it is necessary or at least preferable that the positions of the sieves with respect to the chaffer be varied. It is with this fact in view that the present invention has been designed.

In carrying out my invention I provide a casing 10 secured against the inner faces of the sides A and B of the threshing machine adjacent the free ends of the sieves 75 D and E. Each casing has its edge toward the sieves formed open and the remainder is closed for the purpose of excluding dust and chaff. Disposed at the open edge of each casing is a vertically movable bar 11 80 which bears against the edge of the casing and which has a reduced portion 12 extending thereinto. Each bar 11 is formed with a plurality of notches 13 of any desired number and the free ends of the sieves are 85 engaged within selected pairs of these notches, depending upon whether it is desired to have the uppermost sieve close to or comparatively far from the chaffer. The edge of the reduced portion 12 of the bar 90 11 is formed with rack teeth 14.

In order that the bars 11 may be moved up and down to move the sieves with respect to the chaffer, I provide within each casing 10, a pinion 15 meshing with the 95 rack teeth 14. These pinions are secured upon a shaft 16 which extends transversely through the thresher and which is journaled through the sides thereof.

One end of the shaft 16 projects beyond 100 one side of the thresher and carries a disk 17 and a knob 18 or other suitable handle. The disk 17 has formed in its periphery, a plurality of notches 19. The disk 17 also carries a ridge 20 serving as an indicator. 105 Located on the side of the thresher outwardly of the disk 17, are indicating marks 21 adjacent which are located legends indicating the highest, lowest, and intermediate positions of the sieves and these legends are 110 shown as being "Raised," "Center" and "Lowered." Intermediate mark may also

be provided. Pivoted upon the side of the thresher is a spring-pressed pawl 22 having a finger 23 adapted to enter any one of the notches 19 and the pawl is also provided 5 with a lug 24 by means of which it may be lifted.

The operation of the device is as follows:

The sieves D and E being engaged within selected pairs of the notches 13, when it is 10 desired to bring the sieves relatively close to the chaffer, it is merely necessary that the operator grasp the knob 18 and rotate it until the indicating ridge 20 points toward the mark 21 adjacent the legend "Raised." When 15 the knob 18 is rotated the shaft 16 and pinions 15 will also be rotated and the bars 11 will be moved upwardly by virtue of the engagement of the teeth 14 with the pinions. It will be seen that the sieves will thus be 20 held comparatively near the chaffer. When the disk 17 is moved to this position, the finger 23 on the pawl 22 will engage within one of the notches 19 and hold the parts in 25 position. When it is desired to lower the sieves with respect to the chaffer, the operator disengages the pawl from the notch 19 and turns the knob 18 until the ridge 20 points to the mark adjacent the legend "Center." This will result in rotation of the 30 shaft and pinion and consequent downward movement of the bar 11, carrying the sieves. If it is desired to lower the sieves still more, the knob 18 is turned to bring the ridge thereon opposite the mark adjacent the 35 legend "Lowered." If desired, other indicating marks may be provided in order that the degree of adjustment may be accurately determined.

In some types of threshing machines one 40 end of the chaffer is held in a notch in the bars carrying the sieves. In such an event it is necessary to provide a separate retaining member 25 within which the chaffer is engaged so that it will be absolutely independent of the sieves. This structure is shown in 45 Fig. 6. The member 25 is in exact line with the notches 13 on the bar 11.

Referring to the form shown in Figs. 7 and 50 8, I make use of crank arms 30 carried by a shaft 31 having an adjusting wheel 32. The

arms 30 are connected with blocks 32 notched, as shown, for holding the sieves. The blocks 55 are slidable within guide members 33. In this form the shaft is set higher than the shaft in the previously described form. The operation is, however, substantially the same, the arms 30 merely taking the place of the previously described rack and pinion movement.

In Fig. 9 I have shown the extension board 60 G as disposed entirely above the casing 10 so as to be always above the sieves regardless of the adjustment of the latter.

From the foregoing description and a study of the drawings it will be apparent 65 that I have thus provided an extremely simple and efficient device whereby threshing machine sieves may be adjusted with respect to the chaffer without even necessitating the stopping of the machine, the construction 70 being such that the operator may tell at a glance the positions of the sieves.

While I have shown and described the preferred embodiment of my invention, it is 75 of course to be understood that I reserve the right to make such changes in the form, construction, and arrangement of parts as will not depart from the spirit of the invention or the scope of the subjoined claim.

Having thus described my invention, I 80 claim:

In a threshing machine, including superposed sleeves, of a pair of housings secured upon the inner surfaces of the side of the threshing machine, bars slidably vertically 85 within said housings and formed with a series of notches within selected ones of which the sieves may be engaged, a shaft journaled transversely of the threshing machine and provided with an operating knob 90 exteriorly thereof, the confronting faces of said housings being formed with vertical slots, arms carried by said shaft, and links pivotally connected to the free ends of said arms and pivotally connected with said bars, 95 said last named pivotal connections being accommodated within said slots.

In testimony whereof I affix my signature.

ADOLPH R. FADNESS.
